UNITED STATES PATENT OFFICE.

LOUIS H. PERLMAN, OF NEW YORK, N. Y.

WHEEL.

Specification of Letters Patent. Patented Apr. 9, 1918.

1,262,089.

Application filed September 23, 1916. Serial No. 121,881.

To all whom it may concern:

Be it known that I, LOUIS H. PERLMAN, a citizen of the United States, residing at New York city, in the county of New York and State of New York, have invented certain new and useful Improvements in Wheels; and I do hereby declare the following to be a full, clear, and exact description of the invention, such as will enable others skilled in the art to which it appertains to make and use the same.

This invention relates to improvements in vehicle wheels of the type especially adapted for use on automobiles, and more particularly relates to that type of wheel structure which has come to be known as a cross cut demountable.

The object in view is the provision of simple and efficient locking means adapted to operate in the line of the valve stem and to simultaneously lock the demountable rim on the wheel body and lock the ends of the rim against separation.

With this and further objects in view as will in part hereinafter become apparent and in part to be stated, the invention comprises certain novel constructions, combinations and arrangements of parts as subsequently specified and claimed.

30 In the accompanying drawing—

Figure 1 is a sectional view, the section being taken on a plane substantially between the demountable rim and the wheel body.

35 Fig. 2 is a view in side elevation thereof.

Fig. 3 is a section taken on the plane indicated by line 3—3 of Figs. 1 and 2.

Fig. 4 is an inverted plan view of a modified embodiment of the demountable rim.

40 Fig. 5 is a cross section taken on the plane indicated by line 5—5 of Fig. 4, a part of the wheel body being shown.

Referring to the drawing by numerals, 1 indicates the wood felly of a wheel body on 45 which is mounted the usual felly band or fixed rim 2 having the usual stop flange 3 at its inner edge.

A channeled demountable rim 4 of the cross cut type is mounted on the wheel body and cross cut at the place of the valve stem forming ends 5 and 6. The material of the rim is cut away in semi-circular form at each end 5 and 6 to form an aperture 7 for the passage of the valve stem, and at 55 each end the rim 4 is provided with a triangular plate 8 extending radially inward.

The two plates 8, 8 are located to form substantially a V when the ends of the rim are in operative relation with the apex of the V presented axially outward. The aperture 60 7 extends through the plates 8 for accommodating the valve stem.

A bolt 9 extends through the wood felly 1 at each side of the line of the valve stem opening, it being understood, of course, that 65 the opening 7 registers with a corresponding opening in the wood felly. At the outer side of the wood felly 1 a plate 10 connects the bolts 9 and is itself held in position by said bolts. Substantially midway of the 70 length of the plate 10, and in the line of the valve stem, the plate 10 is provided with an axially outstanding threaded stud 11 on which is threaded a nut 12. A plate or flange 13 is formed with an aperture 14 for 75 the passage of the stud 11, the said plate being arranged between the nut 12 and the plate 10, and formed integral with the upper portion of the plate or flange 13 is a locking wedge 15 which is tapered in a direction 80 for enabling the wedge to exert pressure against the rim 4 in a manner to press the same both radially and axially into position. While no other wedges are shown, it is obvious that any appropriate number of ordinary locking wedges may be distributed 85 about the wheel to coöperate with wedge 15. The wedge 15, however, is distinctive in that it is bifurcated to form a substantially V-shaped opening between the arms of the 90 bifurcation corresponding approximately to the V shape of the plates 8, so that the wedge 15 is adapted to have its arms extend on the opposite sides of said plates 8 and, in operation, to retain the plates against 95 circumferential separation.

In operation, after the rim 4 has been applied to the wheel in the usual manner, the wedge 15 is inserted between the rim and wheel body, the nut 12 having previously 100 been removed from stud 11 and plate 13 is mounted in the stud 11 during the insertion of the wedge 15 into place. When the wedge 15 has reached the point where it can no longer be manually thrust toward its final 105 operative position, the nut 12 is threaded onto the stud 11, and the plate 13 is drawn up for forcing the wedge 15 to its final position. During this movement, the inclined walls of the arms of the bifurcation of the 110 wedge engage the inclined walls of the plate 8 and draw the same in a direction tending

to move the ends 5 and 6 toward each other. The wedge 15 is thus located and then the additional wedges, not illustrated, and of the ordinary locking wedge type, are applied 5 at various points about the wheel.

In Figs. 4 and 5 is illustrated a slight modification to which the same reference numerals have been applied and the same description applies, since the only variation 10 consists of the fact that the locking plates at the ends of the rim are stamped directly from the rim instead of being formed of separate plates and secured to the rim.

The wedge 15 not only effectively serves 15 to retain the ends of the rim 4 in their proper relation, but also serves in coöperation with plates 8 as a driver for the rim. In other words, the wedge 15 and plates 8 20 coöperate to deliver circumferentially directed stresses to and from the rim and to prevent the wheel from creeping circumferentially of the wheel body.

What I claim is:—

1. The combination with a wheel body, of 25 a cross cut demountable rim therefor, the cross cut being in the line of the valve stem opening, and the ends of the rim being formed with projections, and a bifurcated plate movably carried by the wheel body and 30 engaging said projections with the arms of the bifurcation extending on opposite sides of the projections for retaining the ends of the rim against separation.

2. The combination with a wheel body, of 35 a cross cut demountable rim therefor, the cross cut being in the line of the valve stem opening, and the ends of the rim being formed with projections, and a bifurcated wedge movably carried by the wheel body 40 and engaging said projections with the arms

of the bifurcation extending on opposite sides of the projections for retaining the ends of the rim against separation.

3. The combination with a wheel body, of 45 a cross cut demountable rim therefor, the cross cut being in the line of the valve stem opening, and the ends of the rim being formed with projections, a bifurcated plate movably carried by the wheel body and engaging said projections with the arms of the bifurcation extending on opposite sides of the projections for retaining the ends of the rim against separation, a plate connected to the wheel body, and a threaded stud extending from the plate in the line of the 50 valve stem and having an engagement with the bifurcated plate for actuating the same.

4. The combination with a wheel body, of 55 a cross cut demountable rim therefor, the cross cut being in the line of the valve stem opening, and the ends of the rim being formed with projections, a bifurcated plate movably carried by the wheel body and engaging said projections with the arms of the bifurcation extending on opposite sides of 60 the projections for retaining the ends of the rim against separation; a plate at the side of the wheel body, retaining means engaging the plate and extending on opposite sides of the line of the valve stem, and a stud projecting from the plate in the line of the valve stem and having engagement with the bifurcated plate for actuating and 65 retaining the same.

In testimony whereof I affix my signature 70 in presence of two witnesses.

LOUIS H. PERLMAN.
